UNITED STATES PATENT OFFICE.

OTTO L. HEMMING, OF NEW HAVEN, CONNECTICUT, ASSIGNOR TO WINCHESTER
REPEATING ARMS CO., OF NEW HAVEN, CONNECTICUT, A CORPORATION.

POCKET-KNIFE.

1,337,769.

Specification of Letters Patent.

Patented Apr. 20, 1920.

Application filed December 27, 1919. Serial No. 347,741.

To all whom it may concern:

Be it known that I, Otto L. HEMMING, a citizen of the United States, residing at New Haven, in the county of New Haven 5 and State of Connecticut, have invented a new and useful Improvement in Pocket-Knives; and I do hereby declare the following, when taken in connection with the accompanying drawings and the characters 10 of reference marked thereon, to be a full, clear, and exact description of the same, and which said drawings constitute part of this application, and represent, in—

Figure 1. A view in side elevation of a 15 pocket-knife embodying my invention.

Fig. 2. An edge view thereof.

Fig. 3. An enlarged broken plan view of one end of the knife.

Fig. 4. An enlarged broken view partly 20 in side elevation and partly in section of one end of the knife to show one of my improved compensating washers in place.

Fig. 5. A view in transverse section on the line 5—5 of Fig. 3.

Fig. 6. A detached view in elevation of 25 one of the washers.

Fig. 7. An edge view thereof.

My invention relates to an improvement 30 in plural-bladed pocket-knives, the object being to produce at the minimum of expense, a simple and convenient knife constructed with particular reference to positioning the blades and compensating for wear.

35 My invention consists in a plural-bladed pocket-knife having split-and-sprung compensating washers interposed between its handle-frame and the shanks of its blades.

For the illustration of my invention, I 40 have shown a pocket-knife having a U-shaped handle-frame struck up from a single piece of sheet-metal and comprising corresponding side-flanges 2 having rounded ends and a bend 3 forming the back of the knife-handle. This handle-frame receives two 45 blades 4 and 5 respectively mounted upon rivets 6 and 7 passing through the rounded ends of its side-flanges 2, the said blades being located, as usual, on opposite sides of 50 a plane extending through the center of

the knife in the plane thereof. To maintain the blades in these positions, I employ two split-and-sprung compensating washers 8, arranged diagonally opposite each other on opposite sides of the said plane, and 55 mounted upon the respective rivets 6 and 7 aforesaid, one of these washers being interposed between one of the side-flanges 2 of the handle-frame and the heel of the knife-blade 4 while the other washer is interposed 60 between the opposite side-flange 2 of the handle-frame and the heel of the knife-blade 5, as shown in Fig. 2. These washers are formed with slits 9 producing yielding-fingers 10 which are sprung and 65 set as shown in Fig. 7, whereby the washers, when in position, are placed under such tension as to exert a constant effort to hold the knife-blades in their proper relations to each other so that either will close without 70 collision with the other. The friction of the washers also prevents the blades from rattling and takes up wear. In curvature the said washers correspond to the rounded 75 ends of the side-flanges 2 of the handle-frame, the lower ends of the washers being shaped as in 11 to engage with the inner face of the back 4 of the handle-frame, whereby the washers are prevented from turning. A double-ended bowed spring 12 located with 80 in the handle-frame and resting upon the back thereof, engages at its respective ends with the shanks of the blades and holds the same in their open and closed positions.

I claim:

85 A plural-bladed pocket-knife having a handle-frame, a plurality of knife-blades mounted therein, and split-and-sprung compensating washers interposed between the said handle-frame and the shanks of the 90 knife-blades in diagonal arrangement so as to hold the blades in relative position and take up wear.

In testimony whereof, I have signed this specification in the presence of two subscribing witnesses.

OTTO L. HEMMING.

Witnesses:

THOMAS C. JOHNSON,
FRANK A. PAUL.
